UNITED STATES PATENT OFFICE.

JAMES W. PAULLIN, OF RED OAK, IOWA.

SHOW CASE.

Application filed January 6, 1923. Serial No. 611,110.

To all whom it may concern:

Be it known that I, JAMES W. PAULLIN, a citizen of the United States, residing at Red Oak, in the county of Montgomery and 5 State of Iowa, have invented new and useful Improvements in Show Cases, of which the following is a specification.

This invention relates to store furniture and apparatus, particularly to show or display cases, and has for its object the provision of a novel show case including supporting shelves for commodities such as canned, bottled or packaged goods, and further including an elongated compartment provided with a plurality of glazed doors and designed for containing suitable crocks or jars for pickles, mincemeat, salt fish, sauer kraut and the like, the construction of the entire device being such as to 15 make it highly sanitary in use and attractive in appearance.

An important object is the provision of a device of this character in which the compartment is so constructed as to be dust proof while at the same time the glass covers or doors thereof will permit inspection of the contents by a prospective purchaser, the covers furthermore operating to protect the contents against the ravages of 20 insects or rodents.

An additional object is the provision of a show case of this character which will be simple and inexpensive in manufacture, efficient in use, and a general improvement 25 in the art.

With the above and other objects and advantages in view the invention consists in the details of construction to be hereinafter more fully described and claimed and illustrated in the accompanying drawings, in 30 which:

Figure 1 is a front elevation of the device,

Figure 2 is a horizontal section showing a 35 plan view of the bins,

Figure 3 is an end elevation,

Figure 4 is a cross sectional view and

Figure 5 is a rear elevation.

Figure 6 is a detail section showing the 40 shelf mounting and

Figure 7 is a detail section showing the corner construction.

Referring more particularly to the drawings I have shown my device as comprising 45 an elongated cabinet 10 having an inclined open top 11. This cabinet is supported

upon legs 12 and in actual practice the cabinet consists of upper and lower longitudinal bars 13 and 14 respectively at the front and back, connected by upper and lower transverse bars 15 and 16 at both ends, and also at intermediate points if desired, the legs 12 being secured to the longitudinal and transverse bars. The bottom, front, back and both ends of the cabinet are closed, preferably by means of tongue and groove boards 17 suitably secured to the longitudinal and transverse bars. It is of course conceivable that solid panels might be used but as long as there are bound to be joints the tongue and groove structure is preferable for the reason that it positively excludes dust. Any suitable reinforcing structure indicated at 18 may be used at the corners for insuring rigidity.

The rear legs 12 are prolonged upwardly as shown at 19 so as to extend considerably above the cabinet and secured upon the rear side of these upward extensions are brackets 20 which support shelves 21 which are co-extensive in length with the cabinet 10.

The cabinet 10 is intended for the storage of crocks or jars containing pickles, sauer kraut, pickled or salt fish, apple butter, cottage cheese and the like. The cabinet is closed at its top by a plurality of hingedly mounted glazed frames 22 which constitute the covers or doors and these doors are provided with suitable handles 23 so that they may be swung open to permit access to the crocks or jars. A longitudinally extending top piece 12^a is secured to and bridges the space between the upper extension 19 of the rear legs, and located between this top piece and the upper edge of the rear wall of the cabinet 10 is a plurality of closure members 12^b. The forward edges of the shelves are equipped with felt strips 24 which bear against the closure members 12^b for preventing rattling.

From the foregoing description and a study of the drawings it will be apparent that I have thus provided a simply constructed, inexpensive and attractive show case or display cabinet structure which will be highly advantageous in not only presenting the goods in a pleasing manner but which will also operate to preserve the goods in good condition.

While I have shown and described the preferred embodiment of the invention it is of course to be understood that I reserve the

right to make such changes in the form, construction and arrangement of parts as will not depart from the spirit of the invention or the scope of the subjoined claim.

5 Having thus described my invention I claim:

A combination device of the character described comprising an elongated cabinet divided by partitions into a series of similar 10 compartments, glazed hingedly mounted doors normally covering and closing the respective compartments, legs for supporting the cabinet, certain of the legs being

prolonged upwardly to define extensions above the cabinet, a cross piece secured to and bridging the space between said extensions, a plurality of closure members located between said cross piece and the top of the rear edge of the cabinet, a plurality of brackets mounted on said extensions, and shelves mounted on said extensions rearwardly of the closure members. 15

20 In testimony whereof I affix my signature.

JAMES W. PAULLIN.
